UNITED STATES PATENT OFFICE.

FRANK D. HILLER, JR., OF WEBSTER GROVES, MISSOURI, ASSIGNOR TO HIL-KO RIM LOCK COMPANY, OF ST. LOUIS, MISSOURI, A CORPORATION OF MISSOURI.

LOCKING DEVICE FOR DEMOUNTABLE AUTOMOBILE-WHEEL RIMS AND THE LIKE.

1,172,287.

Specification of Letters Patent. Patented Feb. 22, 1916.

Application filed June 17, 1915. Serial No. 34,664.

To all whom it may concern:

Be it known that I, FRANK D. HILLER, Jr., a citizen of the United States, residing at Webster Groves, St. Louis county, Missouri, have invented a certain new and useful Improvement in Locking Devices for Demountable Automobile-Wheel Rims and the like, of which the following is a specification, reference being had to the accompanying drawing, forming a part thereof.

This invention relates generally to automobile wheels and the like and, more particularly, to that class of automobile-wheels having demountable tire-holding rims, the principal object of my present invention being to provide a simple, inexpensive, and readily manufactured device capable of easy and convenient manipulation and actuation for quickly, efficiently, and rigidly releasably or detachably locking the demountable rim on the wheel.

With the above and other objects in view, my present invention resides in certain novel features of form, construction, arrangement, and combination of parts, all as will hereinafter be described and afterward pointed out in the claims.

In the accompanying drawing, which shows my invention in preferred form, Figure 1 is a fragmentary side elevational view of an automobile-wheel equipped with my invention, the pneumatic or other tire of the wheel being omitted; Fig. 2 is an enlarged transverse sectional view through the same with my new ring-locking device shown in full lines in unlocked position; Figs. 3 and 4 are elevational views showing, respectively, the outer and inner or front and rear faces of the tire-rim engaging lug or member forming part of my new rim-locking device; and Figs. 5 and 6 are, respectively, side elevational and plan views of the same.

Referring to the said drawing, in which like reference characters refer to like parts throughout the several views, 1 indicates the usual wooden felly of an automobile-wheel or the like. Fixed flatwise to and upon the tread-face of felly 1 is a relatively broad or wide hooped or ring-shaped metallic band 2 provided preferably integrally at one, or its inner, side edge with an outwardly and upwardly disposed (reference being had particularly to Fig. 2) flange 3. Projecting laterally and inwardly from band 2 at its opposite, or outer, side edge,

is a continuous or annular flange 4 engaging flatwise upon the outer side face of felly 1. This band 2 with its flanges 3 and 4 constitute what I will term the fixed rim-engaging member.

5 indicates a demountable rim of any approved or standard construction, this rim, which is adapted, as will be well understood, to engage with and hold a pneumatic or other tire (not shown), including oppositely disposed side-portions or flanges 6-6' preferably convexed or curved at their outer or under faces, as illustrated in Fig. 2. In operation or use, rim 5 is adapted to encircle and fit on band 2 with its side portion 6' engaging at its under face with flange 3, as shown in Fig. 2, flange 3 having a correspondingly concaved, curved, or otherwise suitably shaped upper face to engage smoothly, firmly, and positively with the side portion 6' of rim 5. Flange 3 so engaging with rim 5, the rim 5 is demountably or detachably locked on the wheel by my new rim-locking device now to be described.

Transversely fitting loosely through felly 1 and the flange 4 of band 2 and projecting at its opposite ends suitably beyond flange 4 and the opposite side face of felly 1, is a bolt or the like 7 preferably threaded at one end, as at 8, to adjustably receive a securing nut 9, a washer 10 being preferably interposed on bolt 7 between the inner side face of felly 1 and nut 9. At its opposite end, bolt 7 is preferably provided with a squared portion or head 11.

12-12 indicate a pair of small parallel levers preferably suitably fixed together. At their inner ends, however, levers 12-12 are oppositely bent obliquely outwardly, as at 13, and provided longitudinally with approximately parallel cam-extensions 14-14 suitably annularly rounded at their edge and spread suitably apart to flatwise eccentrically engage head 11 of bolt 7 on opposite side faces thereof, as clearly illustrated in Fig. 1. Extending transversely through head 11 of bolt 7 and both cam-extensions 14-14 of levers 12-12, with its ends upset upon the outer faces of the extensions 14-14, is a pivot-pin 15 for pivotally fastening levers 12 and their said extensions 14 permanently to bolt 7.

Loosely interposed on bolt 7 between the outer side face of felly 1 and lever-extensions 14, is a lug or the like which I will

- term the movable rim-engaging member. This member or lug has preferably the shape and form shown in Figs. 3, 4, 5, and 6 and integrally includes a body-portion 16 and a top-portion 17, body-portion 16 being transversely cut-away or apertured within its area, as at 18. At the base of, and opening into, cut-away portion or aperture 18, is a second or reduced cut-away portion or aperture 19 in body-portion 16, cut-away portion 19 being rounded at its base, as at 20, and being of such size or dimensions relatively to the diameter of bolt 7 as to neatly and somewhat snugly accommodate and fit bolt 7 when the movable rim-engaging member is in rim-engaging position. It may be here stated that, as seen in Fig. 1, when the movable rim-engaging member is in locking engagement with the rim 5, cam-extensions 14 of levers 12 are adapted to camwise engage the said rim-engaging member upon its outer face and at opposite sides of said reduced cut-away portion 19 thereof.
- Projecting inwardly or rearwardly from, and forming substantially a part of, top-portion 17, is a flange-extension 21. At its under face, this flange-portion or extension 21 is preferably of such gradual or gentle longitudinal curvature as to neatly and smoothly fit upon and thereby engage with band 2 when the movable rim-engaging member is in rim-locking position, as indicated by dotted lines in Fig. 2. At its upper face, top-portion 17 and its flange-extension 21 are, as shown in Figs. 2 and 5, continuously gently curved, concaved, or otherwise suitably shaped to engage firmly, smoothly, and positively with side-portion 6 of rim 5 when the movable rim-engaging member is in rim-locking position. At its forward edge and centrally rearwardly or inwardly therefrom, top-portion 17 with its flange-extension 21 is apertured or cut-away, as at 22, continuously with cut-away portions or apertures 18 and 19 of body-portion 16, the under face of flange-extension 21 being somewhat roundly undercut or recessed, as at 23, at the base of said cut-away portion 22 to neatly fit and accommodate the periphery of bolt 7 when the movable rim-engaging member is in rim-unlocking position, the movable rim-engaging member being adapted to hang on bolt 7 when in rim-unlocking position, as illustrated in full lines in Fig. 2, with its rim-engaging face uppermost or outermost relatively to the wheel and with bolt 7 at its periphery engaging the movable rim-engaging member at its said recess 23.
- As shown in Fig. 5, body-portion 16 is preferably somewhat thicker at its upper end than at its base, the outer face thereof being somewhat curved or concaved to facilitate coöperation and frictional engagement with cam-extensions 14 of levers 12 when said cam-extensions are actuated to, and when the same are in, rim-locking position.
- On its rear face and at its base, body-portion 16 is further preferably provided with a small somewhat rounded rearwardly extending projection, as at 24, adapted to provide a point of contact or fulcrum upon flange 4 for the movable rim-engaging member when the same, with its flange-extension 21, is being actuated or driven, under the cam action of extensions 14 of levers 12, into locking engagement with the rim 5.
- Rim 5 being mounted in position upon the wheel with its said side-portion 6 engaging, as described, with fixed flange 3 and the movable rim-engaging member being manually or otherwise suitably moved from the position thereof shown in full lines in Fig. 2 to approximately the position thereof shown in dotted lines in Fig. 2, on levers 12 being swung from rim-unlocking position to rim-locking position, or from the position thereof also shown in full lines in Fig. 2 to the position thereof shown in dotted lines in Fig. 2, cam-extensions 14 will camwise engage, as described, with the body-portion 16 of said movable rim-engaging member and thereby first drive said top-portion 17 thereof with its flange-extension 21 into full rim-engaging position and afterward, through frictional camwise engagement with the movable rim-engaging member, positively and securely releasably lock said member in locking engagement with the rim 5, the rim 5 being thereby rigidly locked demountably operatively on the wheel. It is, of course, to be understood that the wheel as a whole may be provided with any desired number of my new rim-locking device, the same being arranged in the form of an annular series around the wheel, levers 12, when in rim-locking position, as shown in dotted lines in Fig. 2, lengthwise projecting radially inwardly toward the hub 110 of the wheel and thus severally occupying but small space and in no way impeding the rotary movement of the wheel or interfering with parts of the car or vehicle upon which the wheel may be mounted.
- To demount the rim 5, it is only necessary to reversely-swing levers 12, when the said movable rim-engaging members are free to fall outwardly away from and out of engagement with the rim 5 and into the position thereof shown in full lines in Fig. 2, the movable rim-engaging members, when in such rim-unlocking position, being suspended upon bolts 7, as before described, in convenient position to be again readily and quickly manipulated and locked into engagement with the rim 5. It may be here stated that cut-away portions or apertures 18 of the movable rim-engaging members are of such width as to somewhat snugly

or bindingly accommodate cam-extensions 14 of levers 12 when said movable rim-engaging members are in rim-unlocking position whereby, on a partial movement of levers 12 to rim-locking position when said rim-engaging members are in rim-unlocking position, cam-extensions 14 will project into, and frictionally engage said movable rim-engaging members at the inner faces of the walls of said apertures and thereby maintain or hold said members in position on said bolts with their said rim-engaging faces uppermost or outermost relatively to the said rotary movement of said members on said bolts when the same are in rim-unlocking position being thus prevented. With the movable rim-engaging members so hanging and engaged upon bolts 7 when in rim-unlocking position, as described, a rim 5, as will be seen, may be easily, quickly, and conveniently removed from, or placed in operative position on the wheel.

I have from experience found my new rim-locking device to be most efficient in positively and rigidly locking and maintaining the demountable rim upon the wheel and that the same may be readily and conveniently manipulated from either rim-locking to rim-unlocking position or from rim-unlocking to rim-locking position, the demountable rim being thus locked or unlocked upon the wheel quickly and without the use of wrenches or other like tools.

I am aware that minor changes in the form, construction, arrangement, and combination of the several parts of my new rim-locking device may be made and substituted for those herein shown and described without departing from the nature and principle of my invention.

Having thus described my invention, what I claim and desire to secure by Letters Patent is:

1. A locking device for demountable wheel-rims including a bolt adapted to transversely engage the felly of the wheel, a lever having a pair of spaced cam-extensions fitting eccentrically upon opposite sides of said bolt, said lever being pivotally fastened at its said extensions permanently to said bolt, and a rim-engaging member loosely fitting on said bolt intermediate of said lever and the felly of the wheel, said lever being adapted, when swung to rim-locking position, to camwise engage at its said extensions with said member to releasably secure the same in locking engagement with the rim.

2. A locking device for demountable wheel-rims including a bolt adapted to transversely engage the felly of the wheel, a lever having a pair of spaced cam-extensions, said lever being pivotally fastened to swing relatively to the bolt, and a rim-engaging member loosely fitting on said bolt

intermediate of said lever and the felly of the wheel, said lever being adapted, when swung to rim locking position, to camwise engage at its said extensions with said member to releasably secure the same in locking engagement with the rim, and to further engage at its said extensions with said member, when said member is in rim-unlocking position, to lock said member from movement on the bolt relatively to said lever.

3. A locking device for demountable wheel-rims including a bolt adapted to transversely engage the felly of the wheel, a lever having a pair of spaced cam-extensions, said lever being pivotally fastened to swing relatively to the bolt, and an apertured rim-engaging member loosely fitting on said bolt intermediate of said lever and the felly of the wheel, said lever being adapted, when swung to rim-locking position, to camwise engage at its said extensions with said member on opposite sides of its said aperture to releasably secure said member in locking engagement with the rim, and to further engage at its said extensions with the inner faces of the walls of the aperture of said member, when said member is in rim-unlocking position, to lock said member from movement on the bolt relatively to said lever.

4. A locking device for demountable wheel-rims including a bolt adapted to transversely engage the felly of the wheel, an apertured rim-engaging member loosely fitting on said bolt, and a lever having a pair of spaced cam-extensions pivotally fastened to swing relatively to the bolt and adapted to camwise engage with said member, when swung to rim-locking position, to releasably lock said member in locking engagement with the rim, said lever being further adapted to project at its said extensions into, and frictionally engage with the walls of, the aperture of said member, when said member is in rim-unlocking position, to lock said member from movement on said bolt relatively to said lever.

5. In a locking device for demountable wheel rims, the combination with a bolt adapted to transversely engage the felly of the wheel and a lever having a pair of spaced cam-extensions pivotally fastened to swing relatively to the bolt, of a rim-engaging member loosely fitting on said bolt, said member having an aperture adapted to receive the extensions of said lever, when said member is in rim-unlocking position, to lock said member from movement on the bolt relatively to the lever.

6. In a locking device for demountable wheel-rims, the combination with a bolt adapted to transversely engage the felly of the wheel and a lever having a pair of spaced cam-extensions pivotally fastened to swing relatively to the bolt, of a rim-engag-

4

ing member having an opening to accommodate said bolt and loosely fitting thereupon, said member having a relatively large aperture continuous with said opening, with the 5 inner faces of the walls of which aperture said lever at its said extensions is adapted to frictionally engage, when said member is in rim-unlocking position, to lock said member from movement on the bolt relatively to the lever.

7. In a locking device of the kind described, a rim-engaging member integrally comprising a body-portion and a laterally

flanged top-portion, said body-portion and said top-portion with its said flange being 15 provided with a relatively large aperture, substantially as and for the purposes described, and said body-portion being provided with a reduced smaller aperture opening into said relatively large aperture and 20 rounded at its base to accommodate a supporting-bolt.

In testimony whereof, I have signed my name to this specification.

FRANK D. HILLER, JR.
